T. A. BRAGG,
GLASS MOLD,
FILED MAR. 25, 1920.

UNITED STATES PATENT OFFICE.

THOMAS A. BRAGG, OF TOLEDO, OHIO, ASSIGNOR TO THE OWENS BOTTLE COMPANY, OF TOLEDO, OHIO, A CORPORATION OF OHIO.

GLASS MOLD.

Application filed March 25, 1920. Serial No. 368,612.

To all whom it may concern:

Be it known that I, THOMAS A. BRAGG, a citizen of the United States, residing at Toledo, in the county of Lucas and State 5 of Ohio, have invented new and useful Improvements in Glass Molds, of which the following is a specification.

My invention relates particularly to a protecting device for use with the mold bottoms 10 on a glass forming machine. In machines of the type herein illustrated, in which each finishing mold is provided with a plurality of mold cavities, it has been found in practice that as the molds are opened, the finished 15 articles which are discharged in rapid succession from the mold, strike the mold bottom in such a manner as to cause rapid wear of said bottom. An object of the invention is to provide suitable means for overcoming 20 this objection, as fully set forth hereinafter.

In the accompanying drawings:

Figure 1 is a fragmentary view showing a portion of a bottle forming machine to which the invention is applied.

Figure 2 is a sectional elevation of the finishing mold.

Figure 3 is a view of the open mold looking in a direction perpendicular to the mold bottom.

In Figure 1 is shown a portion of an Owens automatic bottle blowing machine which comprises a carriage having a series of arms or mold carrying frames 5 which rotate with the carriage about the vertical 35 axis of the machine. Each frame 5 carries a finishing mold comprising sections 6 and 7 mounted to move to and from each other about a pivot pin 8 as an axis. These mold sections are provided with a plurality of 40 mold cavities 9, 10, in which the bottles 11 and 12 are blown to their finished form. The bottom plate 13 is formed with depressions 14 and 15 which shape the bottoms of the bottles.

When the mold, during its travel around the machine axis, reaches the discharging position shown in Figure 1, it is in a downwardly inclined position determined by a cam 16 on which runs a roll 17 carried by 50 the frame 5. At this point the mold sections are automatically separated (by means not shown) and the bottles allowed to fall out. The discharge of the bottles is controlled by

"knock-out" disks 20 and 21 carried on a rock arm 22 on a rock shaft 23 controlled 55 and actuated by a cam 24. For a detailed disclosure of the "knock-out" mechanism, reference may be had to the patent to La France No. 1,319,098, October 21, 1919. The disks 20, 21 are operated to engage the upper 60 ends of the bottles while the mold is opening, and are then lifted to release the bottles, the lowermost bottle 11 being released slightly in advance of the other bottle. The lower bottle is out of the way as the upper 65 bottle 12 falls from the mold.

It has been found in practice that without the use of my invention the bottles 12 as they fall from the mold strike the bottom plate and cause rapid wear, particularly at 70 the edge of the depression 15, as the machine is operating continuously and discharging the bottles at very short intervals. To prevent such wear a striking plate or shield 25 is attached to the bottom plate as by means 75 of a screw 26 in such position that the bottles as they fall from the mold will strike said shield and thus be kept from striking the mold bottom. The plate 25 is readily detachable. It will be understood that the 80 form, size and position of the shield or wear plate 25 may be varied and may also be adapted to various styles of molds.

Other modifications may be resorted to within the spirit and scope of my invention. 85

What I claim is:

1. The combination of a mold comprising separable sections, a mold bottom, and a shield attached to said bottom and projecting upward adjacent the outer edge of said 90 bottom into position to be engaged by articles as they are discharged from the mold and thereby prevent them from striking the mold bottom.

2. The combination with mold sections 95 movable to and from each other, a mold bottom beneath said sections, and a shield attached at the outer edge of said bottom and projecting upward above said bottom in the path of articles being discharged 100 from the mold.

3. In a machine of the character described, a mold bottom plate having a downwardly inclined discharging position, and a shield attached to and projecting upward 105 above said plate at the lower or outer edge

- thereof in position to engage articles being discharged from the mold and thereby protect said bottom plate.
4. In a glass forming machine, the combination of a mold support, a mold comprising an inclined pivot pin, mold sections mounted to swing to and from each other about said pin and extending in a downwardly inclined direction therefrom, a downwardly inclined mold bottom, and a lug at the lower end of said mold bottom projecting upwardly above the surface thereof in the path of articles being discharged from the mold.
5. In a glass forming machine, the combination of a mold support, a mold comprising an inclined pivot pin, mold sections mounted to swing to and from each other about said pin and extending in a downwardly inclined direction therefrom, a downwardly inclined mold bottom, and a lug at the lower end of said mold bottom projecting upwardly above the surface thereof, said mold bottom being formed
- with a plurality of cavities in which articles are formed, said cavities being in line between the pivot pin and lug.
6. The combination of a support, an inclined pivot pin projecting therefrom, mold sections pivoted to said pin and projecting therefrom in a downwardly inclined direction, said sections each having a plurality of cavities, an inclined bottom plate having depressions to register with said cavities, said cavities and depressions being so located that the article being discharged from one will pass over the depression in which another was formed, and a shield protruding above the bottom plate at a point beyond said depressions in position to prevent articles as they are discharged from the mold from striking the bottom plate and deforming a depression therein.

Signed at Toledo, in the county of Lucas and State of Ohio, this 12 day of March, 1920.

THOMAS A. BRAGG.
